INVENTOR

J. S. Wright

WITNESS:

BY Victor J. Evans

ATTORNEY

UNITED STATES PATENT OFFICE.

THOMAS F. DOHERTY, OF TERRE HAUTE, INDIANA.

METAL-BUILDING CONSTRUCTION.

Application filed December 16, 1922. Serial No. 607,384.

To all whom it may concern:

Be it known that I, THOMAS F. DOHERTY, a citizen of the United States, residing at Terre Haute, in the county of Vigo and 55
5 State of Indiana, have invented new and useful Improvements in Metal-Building Construction, of which the following is a specification.

This invention relates to improvements 60
10 in building construction and has especial relation to the construction of metal buildings, the primary object being to provide for the formation of a sealed pocket or dead air space in the wall structure, to prevent 65
15 the passage of heat, cold or moisture and provide a satisfactory insulation for the wall.

Another object of the invention is the provision of a novel method of wall construction, wherein the formation of the above mentioned air space is provided.

With the above and other objects in view, the invention further includes the following novel features and details of construction, to be hereinafter more fully described, illustrated in the accompanying drawings and pointed out in the appended claim.

In the drawings:—

Figure 1 is a fragmentary sectional view 65
30 through a portion of a building constructed in accordance with the invention, the wall construction being shown only in part.

Figure 2 is a like view showing the wall construction in a more finished condition.

Figure 3 is a similar view showing the finished construction.

Figure 4 is a fragmentary elevation of the same with parts broken away and others shown in section.

Figure 5 is a section taken substantially on the line 5—5 of Figure 4.

Referring in detail to the drawings, wherein like characters of reference denote corresponding parts, the reference character 80
45 10 indicates a portion of a foundation wall which is preferably formed of cement and which supports metal eye beam joists 11.

This foundation wall also supports vertical members 12, which are preferably 85
50 formed of angle iron and which may be arranged at the corners of the walls, or may be placed at intervals if so desired. The vertical angle members 12 support angle beams 13, which are arranged horizon-

tally and from which ceiling beams 14 (also 90
55 preferably formed of angle iron) may extend, while roof joists 15 may be supported upon a frame thus formed and these roof joists may have secured thereto a roof, a portion of which is indicated at 16.

In the formation of door and window openings, the frames for said openings are supported upon the foundation wall 10 and secured to the angle beams 13, a window frame being shown in Figure 4 of the drawings. This frame includes spaced vertically disposed angle beams 17, whose lower ends rest upon and are secured to the foundation wall 10 as shown at 17, while angle plates 18 serve to secure the lower 95
60 ends of the angle beams 12 to the foundation wall. The upper ends of the spaced angle beams 17 are secured to the angle beam 13 as shown at 19, while horizontal angle beams 20 connect the beams 17 and provide upper and lower members for the window frame.

The foundation wall 10 and the angle beams 13 are connected by spaced rods 21, which extend vertically downward from 100
65 the outer edge of the beam 13 and have their lower ends anchored in the foundation wall as shown at 22. The opposite ends of the rods 21 extend over the angle beam 13 and are provided with eyes 23, which serve 105
70 as a means of connection with eyes 24 located at the upper ends of rods 25. These last mentioned rods have their lower ends anchored in the foundation wall 10 as at 26, so that the rods 21 provide outer spaced 110
75 rods and the rods 25 inner spaced rods. The rods 21 have secured thereon metal lath or furring 27, and this metal lath or furring is then covered on the outside with a suitable plastic covering 28, which may 115
80 consist of stucco or other suitable finish. The metal lathing 27 is also covered upon its inner face with a coating 29 of plastic material and the rods 21 are embedded 120
85 therein.

The rods 25 also have secured thereto metal lath or furring 30 which provides a foundation for plaster 31 upon the inner face of the wall. The wall thus provided is formed of inner and outer spaced walls, 125
90 leaving an air space 32 therebetween which extends from the top to the bottom wall and throughout its length, the inner beams 17

being spaced apart as shown in Figures 1, 2 and 3 of the drawings to provide for this.

The inner and outer walls formed by the construction just described are provided upon their opposed faces with a lining 33, the said lining being formed of suitable insulating material and being connected at their upper and lower edges as indicated at 34 and 35 respectively, so that a sealed pocket or dead air space is provided which extends from the floor beams to the ceiling.

The floor may be formed of cement or other plastic material as indicated at 36, while the ceiling preferably consists of metal lath 37, which are secured to channel strips 38 and serve as a foundation for the plaster 39. If desired, the plastic material or stucco 28 may be continued over the roof beams 15 as shown at 40.

The invention is susceptible of various changes in its form, proportions and minor details of construction and the right is herein reserved to make such changes as properly fall within the scope of the appended claim.

Having described the invention what is claimed is:—

In a building construction, a foundation wall, a frame resting thereon and including floor beams, horizontal angle beams, and vertical members connecting the foundation wall and angle beams, vertically disposed spaced rods arranged upon the inner and outer sides of the frame and certain of the rods being provided with inverted U-shaped saddles at their upper ends which embrace the angle beams and terminate in eyes, the remaining rods being formed with eyes at their upper ends which are received in the first mentioned eyes, having their lower ends anchored in the foundation wall, metal lathing secured to the rods, a covering of plastic material for the lathing to provide inner and outer spaced walls and means connecting the upper and lower portions of the inner and outer walls to provide a dead air space.

In testimony whereof I affix my signature.

THOMAS F. DOHERTY.
